United States Patent Office

Des. 198,869
Patented Aug. 11, 1964

198,869

CASE FOR BOTTLES OR THE LIKE

Robert L. Beesley and Rudolph H. Matthias, both of Saginaw, Mich., assignors to The Dow Chemical Company, Midland, Mich., a corporation of Delaware

Filed Jan. 21, 1964, Ser. No. 78,300

Term of patent 14 years

(Cl. D58—5)

Fig. 3

Fig. 1

Fig. 4

Fig. 2

FIGURE 1 is a side elevational view of a case for bottles or the like, showing our new design;

FIGURE 2 is an end elevational view thereof;

FIGURE 3 is a top plan view thereof; and

FIGURE 4 is a bottom view thereof.

The dominant features of our design reside in the portions shown by solid lines. The side and end elevational views not shown are the same as those illustrated.

We claim:

The ornamental design for a case for bottles or the like, substantially as shown and described.
